BOWLING ALLEY MASKING UNIT

Henry Dreyfuss, New York, N.Y., assignor to American
Machine & Foundry Company, a corporation of New
Jersey

Filed Feb. 10, 1960, Ser. No. 59,334

Term of patent 14 years

(Cl. D34—5)

FIG. 1.

FIG. 2.

Figure 1 is a front perspective view of a bowling alley masking unit embodying my new design.

Figure 2 is a perspective view of the bowling alley masking unit shown in Figure 1 viewed from the lower left hand corner thereof.

I claim:

The ornamental design for a bowling alley masking unit, as shown.
